Primary Examiner—Jeffrey Asch*Assistant Examiner*—Bridget L Eland(74) *Attorney, Agent, or Firm*—Staas & Halsey LLP(57) **CLAIM**

The ornamental design for the mobile phone, as shown and described.

DESCRIPTION

FIG. 1 is a perspective view of the mobile phone showing our design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.
